The ornamental design for a pressing member for a substrate polishing apparatus, as shown and described.

DESCRIPTION

FIG. 1 is a first perspective view, observed from a front of a first pressing member for a substrate polishing apparatus showing our new design;

FIG. 2 is a second perspective view, observed from a rear thereof;

FIG. 3 is a front view thereof;

FIG. 4 is a rear view thereof;

FIG. 5 is a top view thereof;

FIG. 6 is a bottom view thereof;

FIG. 7 is a right-side view thereof, a left-side view being a mirror image thereof;

FIG. 8 is a first perspective view, observed from a front of a second pressing member for a substrate polishing apparatus showing our new design;

FIG. 9 is a second perspective view, observed from a rear thereof;

FIG. 10 is a front view thereof;

FIG. 11 is a rear view thereof;

FIG. 12 is a top view thereof;

FIG. 13 is a bottom view thereof;

FIG. 14 is a right-side view thereof, a left-side view being a mirror image thereof;

FIG. 15 is a first perspective view, observed from a front of a third pressing member for a substrate polishing apparatus showing our new design;

FIG. 16 is a second perspective view, observed from a rear thereof;

FIG. 17 is a front view thereof;

FIG. 18 is a rear view thereof;

FIG. 19 is a top view thereof;

FIG. 20 is a bottom view thereof;

FIG. 21 is a right-side view thereof, a left-side view being a mirror image thereof;

FIG. 22 is a first perspective view, observed from a front of a fourth pressing member for a substrate polishing apparatus showing our new design;

FIG. 23 is a second perspective view, observed from a rear thereof;

FIG. 24 is a front view thereof;

FIG. 25 is a rear view thereof;

FIG. 26 is a top view thereof;

FIG. 27 is a bottom view thereof; and,
